UNITED STATES PATENT OFFICE.

HUGH RICE, OF YONKERS, NEW YORK.

THIRD-RAIL-BRACKET-CLAMP CAP.

1,383,236.

Specification of Letters Patent. Patented June 28, 1921.

Application filed November 10, 1920. Serial No. 423,157.

To all whom it may concern:

Be it known that I, HUGH RICE, a citizen of the United States, and a resident of Yonkers, in the county of Westchester and 5 State of New York, have invented certain new and useful Improvements in Third-Rail-Bracket-Clamp Caps, of which the following is a specification.

This invention relates to third rail equipment for electric railways, and has particular reference to the bracket structures for supporting and insulating the third rail from the other parts of the mechanism.

Among the objects of the invention is to 15 provide a cover for the third rail bracket clamp, of such a nature as to protect the third rail from corrosion at the joints or adjacent to the porcelain clamping blocks located between the main bracket and in the 20 third rail.

Another object of the invention is to so 25 hang or support the third rail as to afford ample looseness to enable it to slip as may be necessary due to climatic conditions such as expansion and contraction, and thereby preventing any danger of buckling.

A further object of the invention is to 30 reduce the danger and disadvantage of short circuiting, which I have found in my extensive experience to be a common loss, not only of the loss of power, but also the burning of the ties, the rails, and other parts of the equipment.

A still further object of the invention is 35 to provide a protector in the nature of a cushion between the porcelain blocks and the clamping bolt.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to 45 the accompanying drawings, in which like reference characters designate the same parts in the several views, and in which—

Figure 1 is a side elevation of a tie and 50 bracket, and indicating in section the third rail at the clamp.

Fig. 2 is an enlarged view similar to Fig. 1 and indicating in dotted lines the relation

of the sheathing for the rail, the section being on the line 2—2 of Fig. 3. 55

Fig. 3 is a vertical longitudinal section on the line 3—3 of Fig. 2.

Fig. 4 is a plan view.

Fig. 5 is a detail perspective view of 60 the cap.

Referring now more specifically to the drawings I show at 10 one of the brackets for supporting the third rail 11 above the ends of the ties 12. As heretofore practised the upper portion of the rail 11 is 65 embraced at any desired point along its length by means of two companion clamp blocks 13 of any suitable insulating material, such as porcelain. These blocks are grooved transversely across the top as 70 shown at 14 to accommodate a T-headed bolt 15 connected to the upper portion of the bracket. The head of the bolt has hooked engagement at 15' with the block 13 remote 75 from the bracket, and by means of the bolt when its nut 16 is tightened the clamping blocks and third rail are held in place 80 against the top of the bracket, leaving the bottom of the rail 11 properly exposed to the shoe carried by the car. 80

After the third rail is suspended or supported on the brackets there is provided a cover or sheathing therefor as indicated at 17 of any suitable insulating material which is intended to protect the rail from damage 85 due to any source. It is necessary, however, to observe a slight clearance as at 18 between the ends of the sheathing and the ends of the blocks 13. Under ordinary conditions, therefore, rain or the like gathers in the joint at this point and constitutes the source of rapid corrosion and deterioration of the rail. This corrosion is directly responsible not only for the deterioration 95 of the rail, but also the short circuiting of the current, and consequent loss of power and efficiency through the supports.

To overcome the foregoing defect in the rail support is one of the primary objects of my invention, and to this end I provide a 100 cap 20 made of any suitable strong, tough, durable material and preferably of a plastic nature, such as celluloid, fiber, or hard rubber. This cap 20 is cast, molded, or otherwise shaped to conform to the top of 105 the porcelain parts of the clamp, and in-

- cludes consequently two hood portions 21 spanning the vertical longitudinal joint between the two blocks 13, a channel portion 22 projecting downward into the groove 14, and two collar portions 23 fitting snugly against the ends of the blocks 13 and extending lengthwise over a sufficient portion of the sheathing to exclude rain or the like from the joints 18.
- 10 It will be noted that the cap 20 is applicable directly to the clamps as above described and that the clamp bolt 15 is applicable in the same manner as heretofore, lying in the channel 22 of the cap and therefore rendering it impossible for the cap to become displaced. Furthermore, much of the direct contact between the clamping bolt 15 and the other parts of the clamp is relieved by the cap as a cushion. Again, all likelihood of a spark or gap occurring along the joint between the two blocks 13 and from the bolt to the rail, is eliminated by the cap spanning the entire clamp as shown.
- 15 I claim:
- 20 1. The combination with a bracket, a third rail spaced from the bracket, a clamp of insulation embracing the rail, and compression means acting upon the clamp to hold it and

the rail to the bracket, of a cap of insulating material extending across the top of the clamp, substantially as set forth.

2. A device as set forth in claim 1 in which the cap embraces the ends as well as the top of the clamp.

3. The combination with a third rail and supporting means therefor comprising a two-part clamp to embrace the rail and a bolt spanning the top of the clamp, of a cap of insulating material covering the top of the clamp and lying between said bolt and the clamp, whereby the cap is held in place by the bolt.

4. The herein described clamp cap comprising a single continuous piece of insulating material comprising two top hood portions and a channel portion connecting them.

5. A clamp cap as set forth in claim 4 including also collar portions to embrace the ends of the clamp as well as the top thereof.

6. A clamp cap as set forth in claim 4 including, in addition to the hood and channel portions, collar portions designed to embrace the ends of the clamp and extend longitudinally therefrom to exclude rain or the like, substantially as set forth.

HUGH RICE.
